UNITED STATES PATENT OFFICE.

FRANK R. RICHARDS, OF LEBANON, KANSAS.

WIRE-STRETCHER.

1,055,354.

Specification of Letters Patent. Patented Mar. 11, 1913.

Application filed July 17, 1912. Serial No. 710,015.

To all whom it may concern:

Be it known that I, FRANK R. RICHARDS, a citizen of the United States, residing at Lebanon, in the county of Smith and State 5 of Kansas, have invented a new and useful Wire-Stretcher, of which the following is a specification.

This invention relates to wire stretchers, and aims primarily to provide a wire 10 stretcher adapted to be connected to a fence post or the like and to stretch a wire so as to draw the wire past the post to which the stretcher is attached, in order that the wire may be stapled to the post in a convenient 15 and efficient manner.

It is also the object of the present invention to provide a wire stretcher capable of stretching wires in various manners as will be necessary or beneficial in its use, and 20 which may be employed for drawing the adjoining ends of two wire strands together, in order that the ends may be readily connected or spliced.

This invention also contemplates the 25 provision of a wire stretcher which shall be simple, durable, substantial, compact and inexpensive in construction, and which will be simple, convenient and efficient in operation.

With the foregoing general objects outlined, and other objects in view, which will be apparent as the invention is better understood, the present invention resides in the novel construction, arrangement and combination of parts hereinafter set forth and 35 pointed out in the appended claim, it being understood that changes in the precise embodiment of invention herein disclosed can be made within the scope of what is claimed without departing from the spirit of the 40 invention.

The invention has been illustrated in its preferred embodiment in the accompanying drawings, wherein like reference characters have been employed to denote corresponding 45 parts, and wherein,—

Figure 1 is a perspective view of the wire stretcher as in use. Fig. 2 is a fragmental detail of the stretcher.

Referring specifically to the drawings, the 50 present invention embodies in its essentials, a tubular body 3 through which a rod or shaft 4 passes for sliding movements, and an actuating mechanism denoted generally by the numeral 5 carried by the body 3 and 55 co-acting with the rod 4 to slide same relative to the body, the body and rod having

gripping devices as hereinafter more fully pointed out.

The body 3 may be constructed of suitable piping or of any tubular material, and 60 is provided at its rear and front ends respectively, with the heads 6 and 7, the said heads being preferably formed by fastening collars onto the ends of the body. The head 6 is provided at its sides with the hooks 65 8 and is provided with a depending loop or eye 9, and the head 7 is provided with an upstanding loop or eye 10 to which is attached a chain or flexible member 11. This chain 11 provides post-engaging means, the 70 said chain being adapted to be looped or passed around the post and then engaged to the hook 8 on the corresponding side, it being apparent that the body 3 may be arranged at either side of the post which may 75 be most convenient or to which side of the post the wire is to be secured. The body 3 is also provided with an upper longitudinal slot 12 for the purpose which will herein- 80 after appear.

The rod 4 may be constructed of any suitable stock, and is provided along its upper portion with a series of ratchet teeth 13 adjoining the slot 12 in the body 3 and is provided along its bottom with a longitudinal 85 featherway 14. A clevis 15 is pivoted to the rear end of the rod 4, and a hook 16 is carried by the rear end of the rod adjoining the clevis 15, the said hook having an eye or loop engaging the rod. A clamp or 90 gripping device 17 is connected to the clevis 15 by means of a link 18, the said gripping device and the gripping devices hereinafter referred to being of any preferred construction. At its forward end, the rod 4 is provided with a depending or radially projecting member 19, a clamp or gripping device 20 being connected to the free end of the projection 19 by means of a link 21. A clamp or gripping device 22 is also connected to the loop or eye 9 by means of a short 95 length of chain or other flexible member 23.

A clip or strap 24 passes around the body 3 at the rear end of the slot 12 and is provided at its ends with the upstanding ears 105 25, between which is pivoted a pawl 26 which passes through the slot 12 in order to co-operate with the ratchet teeth of the rod 4. The pawl or dog 26 is provided with a tail 27 which is curved upwardly or backwardly for the purpose which will herein- 110 after appear. A coiled wire compression

spring 28 is disposed between the tail of the pawl and the body 3 in order to force the pawl into engagement with the ratchet teeth.

5 The mechanism carried by the body 3 for actuating the rod 4 comprises a lever 29 pivoted or fulcrumed to the body 3, the lever 29 having the inner end thereof forked as designated by the numeral 30 in order to 10 straddle the body 3. The lever or handle 29 projects upwardly from the body, and the fork 30 is pivoted to the bearing 31 brazed, soldered or otherwise secured to the bottom of the body 3. The pawl or dog 32 15 is pivoted between the branches of the fork 30 and passes through the slot 12 of the body to coöperate with the ratchet teeth of the rod 4, the pawl or dog 26 being arranged in rear of the lever 29. It will therefore 20 follow, that when the lever 29 is oscillated, the rod 4 will be moved forwardly step by step as will be apparent. The pawl 32 is provided with a tail 33, the free end or terminal 34 of which is bent inwardly to form 25 a stop which is adapted to strike or contact with the lever 29 when the lever is swung rearwardly sufficiently so as to lift or swing the pawl 32 out of engagement with the ratchet teeth. A leaf spring 35 is also carried by the lever 29 and bears against the pawl 32 to serve as an expedient for forcing the pawl into engagement with the ratchet teeth. A screw 36 is also passed through 30 the bearing 31 and the bottom of the body 3 to enter the featherway 14 so as to serve 35 as a feather for constraining the rod 4 against rotation.

The tail 27 of the pawl 26 is arranged in the path of the lever 29 or in the path of the 40 tail 33 of the pawl 32, so that when the lever 29 is swung rearwardly to raise the pawl 32 out of engagement with the ratchet teeth, the tail 33 of the said pawl 32 will strike the tail 27 of the pawl 26 and in turn lift the 45 pawl 26 out of engagement with the ratchet teeth, so that the rod 4 will be free to slide rearwardly. It will thus be observed, that to disengage the rod 4, the operator need merely swing the lever 29 rearwardly to a 50 sufficient extent, but it will be noted that ordinarily, the rod will be locked against retrograde movement by the pawl 26, the pawl 32 serving to move the rod 4 forwardly in a step by step movement as the lever 29 55 is oscillated.

The present device may be employed in various capacities and manners, examples of which are described directly.

When a wire strand is to be stretched and 60 stapled or secured to a post, the body 3 is located on the proper side of the post and the chain 11 is then looped around the post and engaged to the corresponding hook 8, the clamp 17 then being engaged to the wire 65 strand and the lever 29 being oscillated to

force the rod 4 forwardly so as to give the strand its initial stretching action. After the rod 4 has been forced forwardly as far as it will move, or to its forward limit, the clamp 22 is swung rearwardly and is engaged to the wire strand in rear of the clamp 17, the chain 23 being drawn taut prior to attaching the clamp 22. The clamp 17 is then released, which throws the entire strain on the chain 23, and the lever 29 may then be moved rearwardly to disengage the pawls and permit the rod 4 to be slid rearwardly again, in which event, the clamp 17 may be engaged to the wire strand at a new position rearwardly relative to the clamp 22. 70 The clamp 22 is then disengaged and the oscillation of the lever 29 29 is repeated. This operation may be repeated until the wire strand has been sufficiently stretched or drawn taut, in which event, the free portion 75 of the wire strand is engaged by the clamp 20 carried by the forward end of the rod 4 and is also passed over the hook 16. The clamp 17 may then be released, and the rod 4 may then be forced forwardly slightly to 80 draw the wire strand tightly beyond the post, so that the wire strand may be stapled or otherwise secured to the post in a convenient and efficient manner. With the operation as described, a single operator may 85 stretch the wire and secure same to the post without encountering any difficulty, whereas with the block and tackle and similar devices, two or more operators are necessary, and the stretching of the wire and securing thereof to the post is rendered less 90 efficient and convenient. 95

When the device is to be employed for drawing the ends of two strands together for purpose of splicing, the clamp 22 is engaged to one end and the clamp 17 is engaged to the other end, the chain 11 being passed around the corresponding end and the body 3 to prevent the body from swinging away from the strands as its tendency will be. 105 The lever 29 may then be oscillated to slide the rod forwardly which will serve to draw the ends of the strands together so that they may be readily and conveniently spliced. 110

From the brief descriptions of the two 115 uses of the device, other uses and capabilities will be apparent, and it will also be apparent that the objects aimed at are attained in a satisfactory manner, the present device providing a desirable one for the purposes for 120 which it is designed.

Having thus described the invention, what is claimed as new is:—

A wire stretcher embodying a body, a member slidably engaging the same and having ratchet teeth, a lever pivoted to the body, a pawl pivoted to the lever to coöperate with the ratchet teeth and having a tail the extremity of the tail being bent inwardly to provide a stop arranged to strike the lever 125 130

when the lever is swung rearwardly so as to swing the pawl out of engagement with the ratchet teeth, a pawl pivoted to the body in rear of the lever to coöperate with the ratchet teeth and having a backwardly curved tail lying in the path of the tail of the aforementioned pawl so that the latter pawl is raised out of engagement with the ratchet teeth when the lever is swung rear-

wardly, and a compression spring between 10 the tail of the latter pawl and the body.

In testimony that I claim the foregoing as my own, I have hereto affixed my signature in the presence of two witnesses.

FRANK R. RICHARDS.
